UNITED STATES PATENT OFFICE.

ERIK W. MIKAELSON AND ANDREW A. NEAVE, OF EASTON, PENNSYLVANIA, AS
SIGNORS TO TREADWELL ENGINEERING COMPANY, A CORPORATION OF PENN-
SYLVANIA.

GRINDING MACHINE.

Application filed June 27, 1919. Serial No. 307,083.

To all whom it may concern:

Be it known that ERIK W. MIKAELSON and ANDREW A. NEAVE, citizens of the United States, and residents of Easton, county of Northampton, and State of Pennsylvania, have invented certain new and useful Improvements in Grinding Machines, of which the following is a specification.

This invention relates to grinders, and has particular reference to grinders of the swing type embodying a motor at one end and a grinding wheel and suction housing at the other end, together with an intermediate support at or about the center of gravity of the entire system, the grinder being controlled by the operator in a well understood manner.

An object of this invention is to provide trunnion supporting means for the machine, capable of permitting universal movement of the wheel, as well as swinging movements in various planes, one particularly advantageous result of this invention being that a very long straight surface can be ground, whereas previously proposed suspended types of grinders have been limited as to the extent of surface which could be ground without resetting the work.

A further object of the invention is to provide an improved mounting and arrangement of the exhaust blower whereby it is kept out of the way adjacent the motor end, and a still further object of the invention is to provide a strong and yet simple construction which will withstand hard usage.

Figure 1 is an elevation of a machine embodying the invention.

Figure 2 is a plan view.

Figure 3 is a cross section on the line 3, 3 of Figure 1.

Figure 4 is a section on the line 4, 4 of Figure 2.

Figure 5 is a front elevation.

Figure 6 is a section on an enlarged scale showing the driving mechanism for the wheel, and

Figures 7 and 8 show a modification.

1 represents a foundation carrying a socketed pedestal 2 receiving a vertically disposed stub shaft 3 supported on a bottom stop bearing 4 and held in engagement with the flange 5. Stub shaft 3 carries a frame consisting of angle iron tracks 8 connected at their ends by uprights 9, 9 acting as

stops and the uprights being connected by lower cross pieces 10, 11 being bracing angle plates at each end. This entire structure from the stub shaft 3 is rotatable in the pedestal 2, and is removable by lifting when the clamping ring 6 is released.

The grinder frame consists of a tubular main body 12 adjustably carrying at about its middle portion trunnion ring 13 carrying trunnion wheels 14 to roll on the inner ridge on the tracks 8 so that the dirt will not interfere with rolling. The trunnion ring 13 is clamped to the tube 12 by setscrew 15, so that the tube can be longitudinally adjusted in the ring, but also could be angularly adjusted if desired. By using larger wheels 48 to roll on the floor or ground and hold the motor and wheel elevated, as in Figures 7 and 8, the pedestal and tracks can be dispensed with, and a machine provided which can be used anywhere in the shop or yard where the power can be supplied to the motor by cable. By suitable proportioning and design of the wheels, pedestal and tracks, the machine can be used either on the ground or on tracks as desired.

At one end of the tube 12 is a motor 16, centrifugal exhauster 17 connected to settling chamber 18 and supported by a pipe 19 connected to the hood 20 over the wheel 21 through flexible tube 22, the motor and exhauster being preferably mounted on the same support 23 as shown, this support being clamped to the rear end of the tube 12 as at 24.

At the front end of the tube 12, the grinder carrying frame and housing 25 is rotatably mounted thereon by a joint 26, shown in detail in Figure 6, so as to permit the grinder and its driving connections to be rotatable on the tube. As seen in Figure 6, the tube 12 carries rollers 27 on which the grinder carrying frame 25 bears. 28 is the motor shaft provided at the front end with a separable coupling 29 which receives the front shaft 30, the latter being supported in rear bearing 31 and a front bearing 32 and having a thrust bearing 33. At the front end of shaft 30 is a bevel pinion 34 meshing with a similar gear 35 on grinder shaft 36, the wheel 21 being fastened thereon in the usual manner between collars 37. The grinder shaft 36 is supported in bearings 38 and a thrust bear-

ing 39, carried by the housing 25. The housing is horizontally divided similarly to automobile gearing, and the upper half 40 carries a frame 41 having the controlling handles 42, for the operator to grasp. The frame 41 also supports the hood 20. The hood 20 may be of any desired design, and is preferably provided with a settling chamber 43 as shown, this settling chamber being connected to the flexible tube 22 and being itself carried by a frame 44 extending laterally from the joint member 26. The function of the flexible tubing is to maintain the suction connection while the operator 15 tilts the wheel 20 out of its normal vertical plane. The parts are so mounted and disposed that the grinder head is practically balanced to remain in this vertical plane, weights being used if necessary for 20 this purpose. 45, 46 are deflectors placed in the settling chambers 18, 43 respectively, the purpose of which is to trap as much of the heavy material as possible before it reaches the exhauster 17, it having been 25 found in practice that the exhauster has very little to do but to move air, and hence its bearings do not become worn out by the grit which would otherwise be present. The putting of the blower at the front end near 30 the wheel has been found objectionable for this reason in other types of grinders, it being difficult to keep the bearings in good condition. Similar difficulty has arisen where it was sought to carry off the dust 35 through the tube, as the dust tends to settle in the shaft bearings and sometimes in the gears and has given considerable trouble.

The operation of this machine will be understood from the foregoing description, 40 but it is pointed out that by reason of the travel permitted by the wheels, this machine can cover unlimited territory in a shop or yard and can also work on much larger surfaces, without moving the work, 45 than has been permitted by other machines. Inasmuch as the machine is self-contained and with no auxiliary appendages, same can be practically balanced, and the weight is always supported on the floor or on a 50 solid foundation, it is found to be less tiring to the operator than where he has to manage a heavy mass suspended from the ceiling.

Various modifications and changes may 55 be made in the details herein described without departing from the scope of the appended claims.

What is claimed, is:

1. In a grinder, a motor, a grinding wheel 60 driven thereby, a main body carrying said motor at one end and said grinding wheel at the opposite end, and wheeled supporting means directly carried by said main body intermediate the grinding wheel and the 65 motor, said motor and grinding wheel being

substantially in balance relatively to said supporting means whereby the operator adjacent the grinding wheel end can readily manipulate the grinder over the work.

2. In a grinder, a motor, a grinding wheel 70 driven thereby, a main body carrying said motor at one end and said grinding wheel at the opposite end, a swivel connection between said body and said grinding wheel for permitting variation of the plane of rotation of the latter, and a supporting axle 75 and wheels directly carried by said main body intermediate the grinding wheel and the motor.

3. In a grinder, a pedestal, a rotatable 80 frame carried thereby, a trackway secured to said frame, a grinding machine comprising a grinding wheel and a driving motor, and means for mounting said machine so as to be movable on said trackway.

4. In a grinder, in combination: a pedestal; a vertical shaft journaled in said pedestal whereby the shaft may rotate on its vertical axis; a horizontal trackway supported by the shaft; wheels supported by and rollable on said trackway; a trunnion having a horizontal axis supported by said wheels; a somewhat elongated frame supported by said trunnion; means for grinding supported by said frame, the center of gravity of the frame and grinding means lying in the line of action of the trunnion whereby the grinding means may be given a motion of translation, rotation in a horizontal plane or oscillation in a vertical plane 100 and the said center of gravity may be maintained at a constant elevation.

5. In a grinder, in combination: an elongated frame; a grinding wheel; means for supporting the grinding wheel at one end of the frame whereby it may be oscillated about the longitudinal axis of the frame; a motor supported at the other end of the frame; means for supporting the frame whereby it is movable in both a horizontal plane in 110 motion of translation or rotation and in a vertical plane and the center of gravity is always maintained at a constant elevation.

6. In a grinder, in combination: a frame; a motor supported at one point by said frame; a grinding wheel supported at another point by said frame; a pedestal revolvable upon a vertical axis; a horizontal trackway supported by the pedestal; supporting means movable upon the trackway; means for attaching said supporting means to said frame whereby the frame is movable thereon and the line of action of said supporting means passes through substantially the center of gravity of the system comprising the frame and the wheel and the motor, whereby no movement of the wheel in either a horizontal or vertical plane alters the elevation of the center of gravity 120 of said system.

7. In a grinder, in combination: an elongated frame; a grinding wheel supported by one end of the frame; a motor supported at the other end of the frame; means for driving the wheel by the motor; means for supporting the frame whereby it is movable in both a horizontal plane in motion of translation or rotation and in a vertical plane and the center of gravity is always maintained at a constant elevation. 50
8. In a grinder, in combination: an elongated frame; a trunnion attached to said frame; a wheel journalled at either end of the trunnion and means for supporting said wheels whereby they may revolve and the axis of the trunnion may revolve in a horizontal plane whereby the frame may have a motion of translation, rotation in a horizontal plane and oscillation in a vertical plane. 55
9. In a grinder, a pedestal, a rotatable frame carried thereby, a trackway secured to said frame, a grinding machine comprising a grinding wheel, a driving motor, and a swivel connection interposed between said wheel and said motor to permit variation of the plane of rotation of the former, and means for mounting said machine so as to be movable on said trackway. 60
10. A grinding machine comprising a supporting structure, an elongated arm, power means at one end of and carried by the arm, a grinding tool at the other end of the arm, driving connections between the power means and grinding tool, a pivotal support for the arm, and means whereby the arm may be adjusted in the direction of its length with respect to the pivotal supporting means to balance the arm and parts carried thereby. 65
11. A grinding machine comprising an elongated rock arm with a power unit at one end, a grinding tool at the other end, driving connections between the power unit and grinding tool, and means associated with the axis of rocking of the arm for permitting lengthwise movements of the arm and to balance the arm and permit rocking movements thereof. 70
12. A grinding machine comprising a 75
- supporting structure, an elongated arm pivotedly mounted on said structure, a power member on one end of the arm, a grinding tool at the other end of the arm, driving connections between the power member and the tool, and means whereby the arm may be adjusted lengthwise of the supporting structure without disturbing the pivotal connection. 80
13. In a grinder a turn-table having a trackway positioned thereon, an elongated body portion, a sleeve for encircling said body portion and adjustably connected therewith, trunnions projecting from opposite sides of said sleeve, a wheel on each trunnion adapted to roll on said trackway and upstanding arms carried by said trackway, said arms serving as stops for the wheels and as a means whereby said turn-table may be rotated. 85
14. In a grinder an elongated body portion, a sleeve encircling said body portion near its mid length and adjustably connected therewith, trunnions radially extended from opposite sides of said sleeve, wheels mounted on said trunnions, a motor carried at one end of said body portion, a grinding wheel carried at the other end thereof, and means operatively connecting said motor and grinding wheel. 90
15. In a portable grinder, a motor, a grinding wheel driven thereby, an elongated main body carrying said motor at one end and said grinding wheel at the other end, and a supporting wheel attached on each side of the intermediate portion of the main body, and adapted to run with longitudinal movement of the body on a low supporting surface, said wheels being so positioned that the motor at one end substantially balances the grinding wheel at the other end and permitting the operator at will to traverse the grinding wheel in any direction longitudinally of the body by rolling said supporting wheels on a horizontal surface without vertically shifting the center of gravity of the entire machine. 95
